UNITED STATES PATENT OFFICE.

DIONYSIUS W. TREMBATH, OF NEW YORK, N. Y.

SASH-COUNTERBALANCE.

1,135,227.

Specification of Letters Patent.

Patented Apr. 13, 1915.

Application filed May 15, 1912. Serial No. 697,484.

To all whom it may concern:

Be it known that I, DIONYSIUS W. TREMBATH, a citizen of the United States, and a resident of New York, in the county of New York and State of New York, have invented certain new and useful Improvements in Sash-Counterbalances, of which the following is a specification.

This invention relates to windows and particularly to that class used in connection with dwellings and buildings for business purposes.

One object is to provide a novel device for counterbalancing sashes, so that they may be readily and easily raised or lowered, the device being so arranged as to present no obstacle to the complete removal of the sash, when desired.

A second object is to provide means, combined with the counterbalancing device, to effectually lock the sash against movement, as a protection from burglary, and, finally, to provide such means readily applicable to existing structures or to new installations.

These and other minor objects which will be manifest are attained by the novel construction and arrangement of parts herein-after described and shown in the accompanying drawings, in which:—

Figure 1 is a front elevation of a window, showing the application of my invention at both sides. Fig. 2 is a fragmentary sectional view, showing the operative mechanism, drawn to an enlarged scale. Fig. 3 is a transverse section, taken on line 3—3 of Fig. 1. Fig. 4 is an enlarged transverse sectional view of the counterbalance, taken on line 4—4 of Fig. 2. Fig. 5 is an enlarged front view of a portion of the window sash, and Fig. 6 is a transverse section of the same, taken on line 7—7 of Fig. 5.

The invention comprises sashes 10 and 10', freely slidable, up or down as usual, and having the same general appearance as the usual type. The rear window sash 10', is made narrower than the front sash 10 and runs against a fixed strip 11, at its back, while at its sides are filling strips 12, beyond or outside of which are the vertical members of the window from 13; between the rear and front window sashes are strips 14, having hinges 15, and adapted to swing inwardly, while similar strips 16 are hinged at 17 and are also capable of swinging inwardly thereby allowing the window sashes to be swung inwardly from their normal po-

sition, as shown in full lines in Fig. 3, or removed bodily; when in the normal position as shown, the window is prevented from swinging as effectually as if the strip were rigidly secured. From the sides of the sashes a portion of the stile is removed, and in the spaces thus formed are rigidly secured sheet metal plates 18, bent at an angle, like the character Z, so that their outer sides register with the sash edges and extend along their entire length; in the plates are formed a plurality of regularly spaced slots or perforations 19, having a rounded bottom and angular walls. The inner face 18', also serves as a track or runway against which a revolving part of mechanism further on described contacts. At one side of the window sill is inserted a metal plate 20, set flush with the surface of the sill upon which the window rests. This plate is provided with an opening in which is a pintle 21, the same being a part of the bracket 22, secured to the lower left hand corner of the window sash; similarly near the top of the sash is a duplicate bracket 23 secured on the side of the window frame in register with the lower bracket and formed with it is another pintle engageable with an opening in the projection extending from the bracket 24 set in the side of the window frame. These pintles act in the manner of hinges in permitting the window to be swung inwardly when desired. It is evident also that by raising the pintles and window sashes that they will be free from their bearings, and the sashes as a whole, can be bodily removed.

The counterbalancing device consists of a metal face plate 25, having side plates 26 and 27 adapted to extend into a mortise formed in the side walls of the window frame and held securely in position by means of screws passing through the holes in the face plate 25. Between the side members 26 and 27 is secured a tube 28, through which passes the bolt 29, having a head 30 and a screw threaded nut 31 on its opposite end, the bolt being adapted to draw the sides together, holding the tube 28 rigidly between. Surrounding the tube is a spirally coiled flat spring 32, one end of which is engaged with a slot in the tube 28 and the other end rigidly secured to an annular casing 33, which revolves on the tube, and has integrally formed therewith a cap or cover 34 opposite to which is a

flange 35 and a relatively heavy disk 36 attached rigidly to the flange 35. Equally spaced, at the same radial distance are a number of pins 37, rigidly secured in the 5 disk 36 and extending inwardly to a point near the center line of the mechanism. These pins and the disk form in effect a pin wheel and are so arranged relative to the indentations 19, formed in the metal 10 plates 18 as to coöperate therewith, one of the said pins being in engagement with some one of the perforations at all times when the window is in operative position.

From the foregoing, it is evident that the 15 force of the spring 32 may be transmitted to the disk 36 and in such manner as to cause the pins 37 to press against the lower surface of the indentations 19, thereby exerting a tendency to raise the plate and sash, 20 balancing the same, provided the spring has been properly adjusted with respect to the weight of the sash.

In order to hold the window sash at any 25 point where it may be desired, there is provided a lever 38 having a suitably formed button or head 39, at the end, extending alongside the window sash, where it may be readily accessible, while at the other end it is connected by a pivot 40, to the side plate 30 26 of the counterbalance frame. At about the vertical center line of the mechanism, pivotally connected to the lever 38 by the pin 41, is a latch-link 42, having an opening 43, passing over the head 30 of the bolt 35 29, the said link extending downwardly to a point below the periphery of the disk 36, where it is bent at a right angle 44, its extreme end 45 being turned reëntrantly upward, so as to enable it to extend in between 40 any two adjacent pins 37, locking them against movement.

From the foregoing it will be evident that when the latch-link 42 is depressed by the 45 lever 38, the reëntrantly turned latch end 45 clears the pins 37 allowing the disk to revolve, which it does when the window is raised or lowered; also that the periphery of the disk 36 is permitted to contact with the surface of the plate 18', which affords 50 a smooth and regular surface in operating the window, the disk acting as a guide roller to the window sash.

When it is desired to hold the window closed or in any position, the lever 38 is 55 moved upward, whereupon the latch end 45 is brought in between the pins effectually locking the disk 36 against rotation in either direction, thereby securely holding the window sash wherever it may be placed.

In ordinary light windows a single counterbalance on one side of the window sash will be sufficient, but on heavier windows a counterbalance may be used on each side, the window sash thus being provided upon both its edges with Z-shaped metal plates 65 as shown.

I am aware that spring balances in themselves are not new; also that rack and pinion arrangements have been devised with a similar purpose in view, therefore I do not 70 claim these features broadly as my invention, but

What I do claim and desire to secure by Letters Patent is:—

1. In combination with a window sash and 75 frame, a metal plate secured to the side of said window sash, said plate being formed at an angle so as to present two surfaces facing outwardly, one in advance of the other and toward the front of said sash, said plate 80 being provided with a series of uniformly spaced openings, the openings being in the outer corner portion of the plate, a spring drum mounted at the side of said sash, in the frame thereof, a housing therefor, a disk 85 secured to said drum and so disposed that its periphery contacts with the inner face of said plate, and a plurality of pins set in the side of said disk adapted to engage with the openings in said plate. 90

2. In combination with a window sash and frame, a metal plate secured to the side of 95 said window sash, said plate being formed at an angle so as to present two surfaces facing outwardly, one in advance of the other and toward the front of said sash, said plates being provided with a series of uniformly spaced openings, the openings being in the outer corner portion of the plate, a spring drum mounted at the side of said 100 sash, in the frame thereof, a housing therefor, a disk secured to said drum and so disposed that its periphery contacts with the inner face of said plate, and a plurality of pins set in the side of said disk adapted to engage with the openings in said plate, a lever secured to said drum housing and a link attached to said lever the upturned portion of said lever being adapted to engage with said pins thereby preventing rotation 105 of the disk when the lever is raised. 110

In testimony whereof I have signed my name to this specification in the presence of two subscribing witnesses.

DIONYSIUS W. TREMBATH.
